C. E. HUNT

SPARK PLUG

Filed Feb. 12, 1923

Inventor
C. E. Hunt.

By *John Murphy Jr.*
Attorney

UNITED STATES PATENT OFFICE.

CLAYTON E. HUNT, OF CHARLOTTE, MICHIGAN.

SPARK PLUG.

Application filed February 12, 1923. Serial No. 618,580.

To all whom it may concern:

Be it known that I, CLAYTON E. HUNT, a citizen of the United States, residing at Charlotte, in the county of Eaton and State 5 of Michigan, have invented certain new and useful Improvements in Spark Plugs; and I do hereby declare the following to be a full, clear, and exact description of the invention, such as will enable others skilled in 10 the art to which it appertains to make and use the same.

This invention relates to a spark plug.

It is aimed to provide a generally improved, inexpensive leak-proof and substantially 15 carbon-proof plug capable of ready disassembly for inspection and repair.

Another object is to provide a construction which is insulated in a novel manner as hereinafter disclosed so that it may 20 avoid the usual frangible insulation.

Another object is to provide a construction in which the central electrode may have insulation wrapped around the same and held in place against unwrapping by additional 25 insulation and parts of the plug.

Various additional objects and advantages will become apparent from a consideration 30 of the description following taken in connection with the accompanying drawing illustrating an operative embodiment.

In said drawing:—

Figure 1 is a substantially central vertical sectional view through the improved plug, 35 Figure 2 is a bottom view,

Figure 3 is a cross sectional view on the line 3—3 of Figure 1,

Figure 4 is a cross sectional view on the line 4—4 of Figure 1, and

Figure 5 is a detail perspective view of 40 the bushing employed.

Like reference characters designate like or similar parts in the different views.

Carrying out the invention, an attaching shell 10 of suitable metal is utilized which 45 is adapted to be screwed or otherwise attached as at 11 into the cylinder head of an engine. It will be obvious that the shell 10 may be of any suitable size or shape and with the screw threads 11 of any desired 50 pitch, to adapt it to the cylinder head with which it is to be used.

A suitable nut 12 by means of screw threads at 13 on the same and on the shell 10, is fastened to the latter. Nut 12 is recessed at its lower surface as at 14 in order to accommodate a bushing 15 therein.

Both the nut 12 and bushing 15 are preferably of metal. The diameter of the bushing 15 before application to the recess 14 is oversize with respect to the diameter of recess 60 14 so that it will wedge snugly and tightly in the recess 14. Such wedging action is permissible in view of slits or slots which are provided at 16 longitudinally of the bushing 15 and extending alternately from 65 opposite edges thereof.

Shell 11 has an electrode 17 thereon to contact with the central electrode of the plug which is designated 18. The electrode 18 has a sheet of mica or other suitable insulation which is designated 19, wrapped about the same. Said electrode 18 and mica 19 pass snugly through central openings 20 in the nut 12 and the bushing 15. Thus the sheet of mica 19 cannot become unwrapped. 70 Due to the provision of the slits 16 and the fact that the bushing 15 is normally of oversize, said bushing 15 will exert an inward clamping pressure against the mica to cause 75 it to tightly engage the electrode 18. A metallic nut or abutment 21 is provided on the electrode 18 adjacent the lower end of the latter.

Intermediate the nut or abutment 21 and the bushing 15, a plurality of washers 22, 80 of insulating material, for instance mica, are interposed in tight and intimate engagement with each other to form an insulating body. Some of these washers 22 also extend around the sheet 19 at the portion thereof which 90 projects below bushing 15.

The electrode 18 and sheet 19 also extend above the nut 12. Above said nut 12, a plurality of washers 23, for instance of mica or other insulating material surround the 95 electrode 18 and insulation 19 form an insulating body and to prevent unwrapping of the insulation 19. A metal disk or cap 24 rests on the uppermost washer 23. Electrode 18 extends above the cap 24 and has 100 a clamping nut 25 screw threaded thereon. Above nut 25 a binding nut 26 may be screw threaded so that as usual a wire or conductor may be clamped to the plug intermediate said washers 25 and 26. Shell 10 is usually 105 grounded in the electric circuit as will be understood.

The plug constructed as described will be substantially carbon-proof as it will not leak and will produce a spark sufficiently intense 110 to burn the carbon at the spark gap practically as rapidly as it is produced. Also the

method and means of providing the non-frangible insulation is rapid and inexpensive.

Various changes may be resorted to within the spirit and scope of the invention.

Having thus described the invention, what I claim is:

1. A spark plug having a shell provided with an electrode, a nut threaded to said shell having its bore provided with an enlargement, an electrode to coact with said electrode passing through said bore, insulation wrapped about the second mentioned electrode and extending through the bore, and a bushing located in said enlargement surrounding and compressing said insulation against the second mentioned electrode.
2. A spark plug having a shell provided with an electrode, a nut threaded to said shell, said nut having a recess constituting

an enlargement of its bore, a second electrode, said second electrode having insulation wrapped about the same and passing through said recess, an insulated bushing of oversize fitted in said recess and exerting an inward pressure against said insulation, washers of insulation surrounding said insulation and second electrode below the bushing, an abutment on the second electrode below the washers to coact therewith, washers of insulation about the first mentioned insulation and second electrode above the nut, and a nut on the second electrode above the last mentioned washers.

In testimony whereof I affix my signature in presence of two witnesses.

CLAYTON E. HUNT.
